(57) **CLAIM**

The ornamental design for a gas injector for a semiconductor manufacturing apparatus, as shown and described.

DESCRIPTION

FIG. 1 is a front, top and left side perspective view of a gas injector for a semiconductor manufacturing apparatus, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is an enlarged portion view taken from encircled portion labeled, "FIG. 8," in FIG. 1; and,

FIG. 9 is an enlarged view of FIG. 4.

The even dashed broken lines in the drawings represent portions of the gas injector for a semiconductor manufacturing apparatus that form no part of the claimed design. The dot-dashed lines shown in FIG. 1 and FIG. 8 represent the bounds of the enlarged portion of the claimed design in FIG. 8

1 Claim, 4 Drawing Sheets
